UNITED STATES PATENT OFFICE.

NATHAN B. LEVY, OF SCRANTON, PENNSYLVANIA.

DESIGN FOR A CHARM.

No. 38,162.

Specification for Design.

Patented Aug. 14, 1906.

Application filed June 28, 1906. Serial No. 323,963. Term of patent 14 years.

To all whom it may concern:

Be it known that I, NATHAN B. LEVY, a citizen of the United States, residing at Scranton, in the county of Lackawanna and State of Pennsylvania, have invented a new, original, and ornamental Design for a Charm, of which the following is a specification, reference being had to the accompanying drawing, forming part thereof.

The figure is a face view of a charm, showing my new design.

I claim—

The ornamental design for a charm as shown.

NATHAN B. LEVY.
